P. M. KOENIG.
 COMBINED SHIPPING AND DISPLAY CASE.
 APPLICATION FILED SEPT. 13, 1916.

1,235,521.

Patented July 31, 1917.

UNITED STATES PATENT OFFICE.

PAUL M. KOENIG, OF ATASCADERO, CALIFORNIA.

COMBINED SHIPPING AND DISPLAY CASE.

1,235,521.

Specification of Letters Patent.

Patented July 31, 1917.

Application filed September 13, 1916. Serial No. 119,990.

To all whom it may concern:

Be it known that I, PAUL M. KOENIG, a citizen of the United States, residing at Atascadero, in the county of San Luis Obispo 5 and State of California, have invented a new and useful Combined Shipping and Display Case, of which the following is a specification.

This invention is designed to provide a 10 shipping case for the use of seedmen and other dealers in goods that are put up in more or less uniform packets such as for instance packets of garden and flower seeds, and an object of the invention is to provide 15 a shipping case for such packets, in which the packets may be packed when the case is open and in which they may be inclosed for transportation and may afterward be exhibited in a manner attractive to the customer and convenient for the dealer when 20 the case has again been opened.

The invention comprises a hollow base having a slotted side and a slotted cover, the slots of which register with each other, 25 an adjustable section or tray pivoted to said base and adapted to be brought into various angular relations to the top of the base and provided with receptacles open on one side and adapted to form separate display containers, and in carrying out the invention 30 I have constructed said tray with slotted partitions arranged parallel to the base and with partition slats extending through the slots of the slotted partitions and extending 35 into or working in slots in the top and in the rear wall of the base. I have also pivoted the slotted partitions in the adjustable section so that they may be adjusted to different angular relations to the base and to 40 the walls of the adjustable section.

The adjustable section is also provided with means whereby it may be supported aslant relative to the base when the case is open and adjusted to favorably display 45 goods contained therein.

Objects of the invention are cheapness, simplicity, ease of adjustment of case for display; and security of fastening and rigidity of case for shipping.

50 Other objects, advantages and features of invention may appear from the accompanying drawings, the subjoined detail description and the appended claims.

The accompanying drawings illustrate the 55 invention.

Figure 1 is a perspective view of the combined shipping and display case in display position, the cover being omitted.

Fig. 2 is a sectional elevation of the case as shown in Fig. 1. Line x^2-x^3 , Fig. 4, 60 indicates the line of section.

Fig. 3 is a section of the closed shipping case on line x^2-x^3 , Fig. 4.

Fig. 4 is a section on line x^4 , Fig. 3.

Fig. 5 is a fragmental sectional detail 65 analogous to Fig. 4 showing a concealed pivot arrangement.

Arrows on the section lines indicate the direction of sight in the sectional views indicated by such lines.

70

The base 1 may be constructed of boards, shooks or any other firm strong sheet material adapted for making boxes and cabinets and comprises a bottom 2, front wall 3, slotted rear wall 4, end walls 5, cleats 6 75 on said end walls, a movable base top 7 mounted on said cleats and flush with the top of the four walls of the base. The rear wall 4 and the top 7 are provided with registering slat-receiving slots 8, 9. A tray 80 10 comprising a bottom 11, side walls 12, end wall 13 and slotted partitions 14 is mounted outside of the base, and is pivoted by pivots 15 to the end walls 5 of the base; the side walls 12 of the tray being spaced 85 apart and extended beyond the tray bottom 11 to embrace the end walls of the base. The extensions 16 of the sides of the tray are pivoted to the end walls 5 of the base by pivots 15 which may be screws axially 90 aligned and connecting the base and the side extensions of the tray. By inserting the screws so that their heads 17 are on the inner side of the base, as in Fig. 5, the pivots are concealed from view.

95

The tray is provided with partitions 14 arranged parallel to the pivot axis and fastened to the side walls of the tray by means of pivots 18 which are arranged co-axially with each other and parallel to the base so 100 that the partitions may be brought into different angular positions relative to the bottom 11 of the tray. A removable cover 19 is fitted to the top of the base and tray when said base and tray are extended in flat 105 position. The bottom 11 of the tray abuts against the rear wall 4 of the base when the tray and base are extended in the same plane, and means as indicated by the screws 20 are provided to hold the cover 19 on the 110

base and tray, thus to hold base and tray in rigid relation to each other to constitute a shipping case.

The transverse partitions 14 are provided with slots 21 alined with the slots 8 and 9. Slats 22 fastened by any suitable means as tacks 23 driven through flanges 24 into end wall 13 of the tray, extend through the slots 21, and through slots 8 and 9. Said slotted partitions extend between the side walls of the tray and are in pivotal relation to the base and to the tray side walls 12, so that when the cover 19 is removed the tray can be raised to a slanting position and the partitions 14 may be adjusted to different angles and inclinations to hold the packets in a desired position for display.

The base is hollow and the base top 7 is loose and easily removed so that a reserve store of seed packets or other goods may be contained therein and concealed while the other packets are displayed.

Supporting means as the brace or prop 25 having a pivot 25' temporarily engaged with the bottom 11 by suitable means as the screw eye 26, is provided to support the tray aslant as shown in Fig. 2.

The ends of the extensions 16 are oblique to the edges thereof and the lower corner 16' thereof is near to the pivot 15 so that said corner will escape any flat surface of the support upon which the case may stand, thus allowing the tray to be elevated to slanting position. The tips 16'' of said extensions are adapted to impinge upon such supporting surface when the tray is thus aslant so that the brace 25 may meet a firm resistance and the display case thus be firm and rigid when in the position shown in Fig. 2.

The tips 16'' and the foot of the prop 25 coöperate as a tripod to give stable support to the tray on a flat surface or on an irregular surface that may be practicable as a support for the case and said foot may be made more or less pointed as may be deemed desirable.

A vacant chamber 28 is provided above the bottom 11 and between the lower partition 14 and the rear wall 4 of the base to receive the brace 25 when the case is packed and before the cover is applied.

The slats 22 are narrower than the slots 21 so as to allow the partitions 14 to rock on the pivots.

A stop 27 is fixed to the end of the bottom 11 and serves to reinforce said end where it abuts against the end wall 4 of the base.

In practical use the tray will be packed with the goods while in the flat position shown in Figs. 3 and 4, the cover 19 and the base top 7 being removed. Then the brace 25 will be stored in the chamber 28 and the top 7 and the cover 19 will be applied and the cover fastened in place by the screws 20.

The case is then ready for marking and shipping.

To display the goods, the cover is removed, the tray tilted and the slotted partitions adjusted to such angle as may be appropriate to hold the packets in the best position for display.

The base top 7 may be raised and reserve packets removed from time to time to replenish the display stock in the tray.

75

I claim:

1. A shipping case comprising a base, a tray mounted outside of, extending from, and connected to the base and adjustable to various angular positions relative thereto, so a removable cover for the tray and base, and means to detachably fasten the cover in place to hold the tray and base in rigid relation to each other.

2. In a display case the combination with a base, of a tray pivoted to the base outside thereof and extending therefrom, a cover, and means to detachably fasten the cover in closing position on the base and tray.

3. A combined shipping and display case comprising a base, a tray pivoted to the base and provided with partitions arranged parallel to the pivot axis, cover means adapted to fit on the tray and base to hold them in rigid relation to each other, and means to fasten said cover means on said tray and base.

4. A combined shipping and display case comprising a base, a tray pivoted to the base and provided with partitions pivoted to the tray by pivots that are parallel to the pivot axis, cover means adapted to fit on the tray and base to hold them in rigid relation to each other, and means to fasten said cover means on said tray and base.

105

5. A combined shipping and display case comprising a base provided with slots in its top and one side, a tray pivoted to the base and provided with slotted partitions parallel to the pivot axis, and slat means extending through the slots of said partitions, wall and top.

110

6. A combined shipping and display case comprising a base provided with slots in its top and one side, a tray pivoted to the base and provided with slotted partitions parallel to the pivot axis, slat means extending through the slots of the partitions and through the slots of said wall and top of the base, a cover for the tray and base, and means to temporarily fasten the cover on the tray and base to hold the same in rigid relation with each other when the case is used for shipping.

115

7. A shipping case comprising a base; a tray provided with extensions pivoted to the base provided with a tip to impinge upon a supporting surface when the tray is aslant; a removable cover for the tray and base; means to detachably fasten the cover

120

125

130

in place to hold the tray and base in rigid relation to each other and a detachable brace to support the tray aslant with said tip impinging upon the surface on which the base may stand.

8. In a display case the combination with a base of a tray having extensions pivoted to the base, and provided with a tip to impinge on a supporting surface; and means to support the tray aslant with the tip impinging on the surface on which the base may stand.

9. A combined shipping and display case comprising a base, a tray pivoted to the base and provided with partitions arranged

parallel to the pivot axis; a cover adapted to fit on the tray and base to hold them in rigid relation to each other; means to fasten the cover on the tray and base, and a detachable prop for the tray; there being a 20 vacant space in the tray below the lower partition to store the prop when it is detached and the cover is in place.

In testimony whereof, I have hereunto set my hand at Atascadero, California, this 25 6th day of September 1916.

PAUL M. KOENIG.

Witness:

ORRIN SLOAN.
